COMBUSTION AIR REGULATING MEANS
FOR FIREBOXESVerdrie F. Clark, New Albany, Ind., assignor to
Peerless Manufacturing Corporation, Louis-
ville, Ky., a corporation of Kentucky

Application March 29, 1938, Serial No. 198,750

2 Claims. (Cl. 137—152)

This invention relates to means for regulating the supply of combustion supporting air to stoker-fed, solid-fuel-burning furnaces or the like, particularly, but not necessarily of the underfeed type in which feeding of the fuel is automatically controlled by the demand on the furnace or the like, and has for its general object to provide a simple, inexpensive, easily installed, reliable and efficient air supply regulating means which is controlled by the condition of the fuel bed in the furnace or the like to insure the supply of approximately the proper amount of air to said fuel bed to maintain an approximately ideal condition thereof during all periods of operation of the furnace or the like.

Another object of the invention is to provide a means for the purpose stated which is adjustable for proper operation in any given installation and for any given setting of the thermostat, aquastat, pressure responsive device or other device by which feeding of the fuel is automatically controlled.

With the foregoing and other objects in view, which will become more fully apparent as the nature of the invention is better understood, the same consists in the novel features of construction, combination and arrangement of parts as will be hereinafter more fully described, illustrated in the accompanying drawings and defined 30 in the appended claims.

In the accompanying drawings, wherein like characters of reference denote corresponding parts in the different views:

Figure 1 is a side elevation, partly in section, of an underfeed, stoker-fed stoker equipped with the present combustion-air supply regulating means.

Figure 2 is a top plan view of the assemblage shown in Fig. 1.

Figure 3 is an enlarged side elevation, partly in section, of a portion of the air tunnel and the air flow regulating dampers of the invention; and

Figure 4 is a top plan view of the assemblage shown in Fig. 3.

Referring to the drawings in detail, A designates, generally, a firebox or pot which, within the purview of the invention, may have a variety of specifically different forms, and B designates, generally, a means for feeding fuel to the firebox or pot A from a supply bin or the like C and which, within the purview of the invention, may likewise have a variety of specifically different forms.

As illustrated in the present instance, the firebox or pot A is of the underfeed type and comprises an open-top retort 10 surmounted by a series of tuyères 11.

Spaced outwardly from and surrounding the tuyères 11 is a wall 12 which may comprise a downward extension of the uppermost tuyère and 60 which defines a closed-top, open bottom air space

13 around the tuyères from which air may enter the firebox or pot through openings 14 in the tuyères.

The retort 10 is disposed within a plenum chamber or wind-box 15, and the wall 12 rests at its bottom on the top wall of said plenum chamber or wind-box 15 outwardly of an opening 16 in said top wall through which the upper portion of the retort 10 extends and which is of greater diameter than the said upper portion of said retort. Accordingly, air supplied to the plenum chamber or wind-box 15 is free to flow therefrom into the air space 13 surrounding the tuyères 11 and through the openings 14 in said tuyères into the firebox.

A fuel supply tube 17 is connected with a bottom portion of the retort 10 and leads to said retort from any suitable source of fuel supply, as, for example, the bin C, and in said tube is a screw 18 or any other suitable means for conveying coal or other fuel to the retort 10 and delivering it 20 upwardly through the open top thereof into the firebox or pot proper comprised by the tuyères 11.

As will be understood, an electric motor (not shown) is suitably geared to the screw 18 for driving the same, and operation of said motor is 25 controlled by a thermostat, aquastat, pressure responsive device or the like, depending upon whether the installation is for air or water heating or steam generating purposes, so that fuel is delivered periodically to the firebox or pot A in 30 accordance with the demand for heat, this being in accordance with well known practice and being deemed therefore not to require illustration nor more extended description.

Driven by the same motor which drives the 35 screw 18 or, if preferred, by a separate motor under the same control as the screw driving motor, is a fan or blower 19 which may have any convenient location and which is connected with the plenum chamber or wind-box 15 by an air duct 20 40 so as to periodically supply combustion air to the fire in harmony with the periodic supply of fuel thereto.

The general combination so far described in which a fuel supply means and a combustion air 45 supply means operate in harmony with each other to deliver fuel and air to a firebox or the like periodically in accordance with the demand for heat, is well known and operates satisfactorily if the time periods between successive operations 50 are of short duration and the condition of the fuel bed does not appreciably change during such time periods. However, there are frequent time periods of more or less long duration between successive operations of the fuel feeding and air 55 supply means when holes may burn in the fuel bed. Then, when the next operation occurs, the air rushes through the holes in the fuel bed, delivers excess oxygen to the fire at localized points, which results in a dearth of oxygen at 60

other points, and, in general causes an inefficient combustion condition in the firebox.

The means comprising the present invention is specially designed not only to insure against any prolonged rush of air at high velocity through holes which may burn in a fuel bed, but to assure at all times the supply of approximately the correct amount of air to the full bed to properly support combustion of the fuel under all conditions of operation of the furnace or the like, so that an approximately ideal condition of the fire is constantly maintained.

Essentially, the present air supply regulating means comprises a pair of freely swingable, operating dampers 21 and 22 mounted in the air duct 20 in suitable spaced apart relationship longitudinally of said duct.

The damper 21 is disposed in advance of the damper 22, that is, nearer the firebox A than the damper 22, and may conveniently comprise a flat plate mounted at or near its top on a horizontal shaft 23 which extends transversely of the air duct 20 at or near the top thereof and is journaled in the duct side walls or in suitable bearings carried by said side walls.

One end of the shaft 23 is provided with an arm 24 which extends at right angles, or at substantially right angles, to said shaft and which may appropriately be provided by a bent end portion of said shaft. This arm is disposed outwardly of the adjacent side wall of the duct 20 and is provided for cooperation with a stop 25 to limit opening movement of the damper 21. The stop 25 is carried by a segmental plate 26 which is disposed between the arm 24 and the adjacent side wall of the duct 20 and which is mounted in any suitable manner, as upon the shaft 23 or upon one of its bearings, for rotatable adjustment about the axis of said shaft. Accordingly, by rotatably adjusting the plate 26 the position of the stop 25 may be varied to predetermine the limit of opening movement of the damper 21.

Any suitable means may be provided to secure the plate 26 in any desired position of adjustment. In the present instance said plate is provided with an arcuate slot 27 through which extends a stud 28 which is fixed with respect to the air duct 20 and which has threaded thereon, outwardly of said plate 26, a wing nut 29. When the nut is loosened the plate is free to be normally adjusted, and by then tightening the nut the plate is clamped in its adjusted position against the adjacent side of the air duct. On the side wall of the air duct are indices 30 and on the plate 26 is a pointer 31 for cooperation with said indices to afford an indication of the limit of opening movement of the damper 22 for any given adjustment of the plate 26. Obviously, this arrangement may be reversed by providing the indices 30 on the plate 26 and by providing any suitable fixed pointer for cooperation with such indices.

The damper 21 tends constantly, under the influence of gravity, to swing to a position closing the air duct 20, and it is swingable by the pressure thereagainst of combustion air supplied through said duct by the fan or blower to an open position.

The damper 22 is mounted at or near its top on a horizontal shaft 32 which extends transversely of the air duct 20 at or near the top thereof and is journaled in the duct side walls or in suitable bearings carried by said side walls.

One end of the shaft 32 is provided with an arm 33 which extends at right angles, or at substantially right angles, to said shaft and which may

appropriately be provided by a bent end portion of said shaft. This arm 33 is disposed at substantially right angles to the damper 22, or in any other suitable relationship thereto, and, is suitably weighted, as indicated at 34, so as to tend constantly to swing said damper upwardly and rearwardly with respect to the direction of air flow through the duct 20, to a fully or partly open position as determined by engagement of the arm 33 with an adjustable stop 35 which, as in the case of the stop 25, may be carried by a segmental plate 36 rotatable about the axis of the shaft 32 and capable of being clamped in different rotatably adjusted positions by a wing nut 37 on a stud 38 extending from the adjacent side wall of the air duct 20 through an arcuate slot 39 in said plate.

A suitable fixed stop, such as a lug 40 on the duct 20 to be engaged by the arm 33, is provided to prevent swinging movement of the damper 22 from a fully or partly open position thereof beyond a position in which it closes, or substantially closes, the air duct 20, and, in order to indicate the limit of opening movement of said damper, as determined by adjustment of the plate 36 and the stop 35 carried thereby, said plate 36 is provided with a pointer 41 for cooperation with a series of indices 42 on the adjacent side wall of the duct 20. Moreover, the weight 34 is adjustable along the arm 33 to require the exertion of more or less pressure against the damper 22 to swing same to its closed position. To this end, the weight 34 may comprise, as shown, a pair of cooperating lock nuts threaded on the arm 33, or simply a body of metal slidably along said arm and capable of being secured in adjusted position by a set screw, in accordance with well known practice.

The free end portion 22a of the damper 22 is inclined downwardly or forwardly to the general plane of said damper so that when the latter is in a fully or partly open position the said portion 22a is disposed to have air, driven through the duct 20 by the fan or blower 19, impinge against the rear face thereof. Accordingly, dependent upon the adjustment of the weight 34 and a more or less fully open position of the damper as determined by adjustment of the stop 35, a greater or lesser velocity of air flow through the duct 20 will be required to swing said damper to closed position.

The air duct 20 may be specially constructed to have the dampers 21 and 22 and their related parts associated therewith, or said dampers and their related parts may be assembled with a suitable casing 43 to be applied to the duct 20 in any suitable manner after cutting an opening in the duct to admit the dampers thereto. In the latter case, which is a convenient manner of applying the dampers to the air ducts of old installations, the walls of the casing 43 become, to all intents and purposes, parts of the walls of the duct 20. Accordingly, it will be understood that when reference is made herein to the walls of the air duct, such walls may be either the walls of the duct itself or the walls of a casing or equivalent element such as the casing 43.

The ideal condition in the firebox A is a state of incandescence at all times when the fuel feeding means and the combustion air supply means are operating, and this condition may substantially be assured by a proper adjustment of the weight 34 along the arm 33 to obtain a proper balance between the air supply and the fuel supply. In other words, by a proper adjustment of the weight 75

34, the damper 22 will remain in its fully or partly open position, as determined by adjustment of the stop 35, as long as the fire is in an ideal incandescent condition. If, on the other hand, the fire tends to burn too rapidly, that is, faster than the predetermined supply of fuel thereto, it will begin to assume a condition offering lesser resistance to the flow of air therethrough. The air then will begin to flow at increased velocity 10 through the duct 20, but then its increased velocity will result in swinging of the damper 22 toward closed position, reducing the volume of air reaching the fire and consequently retarding combustion and permitting the amount of fuel 15 in the firebox to increase. With increase of fuel in the fire box the flow of air through the fuel bed is retarded and the resulting back pressure created in the air duct 20 results in a reduction in the velocity of the supplied air. The weight 20 34 then acts to further open the damper 22 and to restore the balanced condition between the air supply and the fuel supply.

The operations recounted may occur at more or less frequent intervals and to greater or lesser extents whenever the fuel feeding means and the air supply means are in operation, with the result, as is apparent, that although the condition of the fire may fluctuate slightly, it never deviates greatly from an ideal incandescent, or substantially ideal incandescent condition.

As long as air is being supplied through the duct 20 it holds the substantially balanced damper 21 in an open or partly open position, depending upon the velocity of the air, but as soon as operation of the fuel feeding means and the fan or blower 19 ceases, as when the required amount of heat has been developed, the damper 21 gravitates to closed position and the damper 22 is swung by the weight 34 to its open position. The fuel bed then begins to assume a banked condition, and if the period of inoperativeness of the fuel feeding means and the air supply means is of short duration the inherent character of the fuel bed may not change appreciably. If, then, the fuel feeding means and the air supply means again begin operating the result is substantially the same as if there had not occurred any interruption in their operation. If, on the other hand, the period of idleness of the fuel feeding means 50 and the air supply means is of a duration such that holes burn in the banked fuel bed, then, when the fuel feeding means and the air supply means again are operated, the high velocity flow of air through the duct 20 permitted by the holes 55 in the fuel bed, results in the damper 22 being swung to a more or less fully closed position, thereby cutting off or reducing the flow of air to the firebox to an extent to permit fuel to be fed to the firebox at a much more rapid rate than it is consumed until the holes in the fuel bed are filled. As said holes become filled and retard the air flow, the damper 22 opens until there is restored a balance between the feeding of the fuel and the air supply, and when this balance is attained the damper 22 operates as first recounted to substantially maintain the fire in a condition of incandescence.

The damper 21 serves two purposes. First, it acts as a banking damper to deny or reduce flow 70 of natural draft to the firebox during periods of idleness of the fuel feeding and air supply means. Second, it serves to predetermine the maximum amount of air to be delivered to the firebox. In other words, by adjustment of the stop 25 to limit

the opening movement of the damper 21, the maximum effective cross sectional area of the air duct 20 may be varied and may be made such that, when the fuel supply means is regulated for operation at lesser than capacity, an excess of 5 combustion air will not be delivered to the firebox.

In addition to its advantages respecting the regulation of draft, the means comprising the present invention accomplishes the elimination, or substantially the elimination, of the disadvantages respecting so-called "fly ash." Heretofore, when holes burned in the fuel-bed and air rushed through such holes, fine particles of ash were carried into the boiler passes, radiators or the like, with the result of obstructing the same 15 and insulating their surfaces. However, since, according to the present invention, rush of air through holes in the fuel-bed ceases practically as soon as it begins, little or no ash is carried into the boiler passes, radiators or the like. 20

Without further description it is thought that the features and advantages of the invention will be readily apparent to those skilled in the art, and it will of course be understood that changes in the form, proportion and minor details of construction may be resorted to, without departing from the spirit of the invention and scope of the appended claims. 25

I claim:

1. Air flow control means comprising a duct 30 having a top opening, a casing element detachably mounted on said duct in closing relationship to said top opening, said casing element having side, top and end walls, the top wall of said casing element being disposed above the top wall of said duct, a horizontal pivot member extending transversely of said casing element approximately in the plane of the top wall of the duct, said pivot member being journaled in the side walls of said casing element, a damper mounted upon said pivot element and having portions extending in opposite directions therefrom, one portion to close the space between said pivot member and the bottom of the duct and the other portion to close the space between said pivot member and the top wall of said casing element when the damper is closed, means tending constantly to swing the damper to an open position in which it extends longitudinally of the duct near the top wall thereof, and means whereby air flowing 50 through the duct in excess of a predetermined velocity swings the damper toward closed position. 45

2. Air flow control means comprising a duct, a damper within said duct having a horizontal pivot disposed transversely relative to the duct adjacent to the top thereof, said damper having portions extending to opposite sides of said pivot, one portion to close the space between said pivot and the bottom of the duct and the other portion to close the space between said pivot and the top of the duct when the damper is closed, means tending constantly to swing said damper to an open position in which it extends substantially longitudinally relative to the duct near the top wall thereof, the free end portion of said first mentioned portion of said damper being formed to extend downwardly when the damper is in its open position extending substantially longitudinally relative to the duct so as to be acted upon by air flowing through the duct in excess of a predetermined velocity to initiate closing movement of the damper. 60 65 70

VERDRIE F. CLARK.
